UNITED STATES PATENT OFFICE

SAMUEL DAVIDOFF, OF MILWAUKEE, WISCONSIN

POCKET REINFORCEMENT

Application filed July 30, 1927. Serial No. 209,435.

My invention relates to improvements in pocket reinforcements in pocketed garments.

Where the pockets are actually used to carry objects that have some weight, the lower 5 margins of the pocket opening usually stretches and becomes misshapen so as to mar the appearance of the garment generally and cause the pocket to catch upon projecting objects.

10 It is an object, therefore, of my invention to provide a device for reenforcing the margins of the opening of a pocket so as to interfere as little as possible with the easy use of the pocket and to provide an adequate reinforcement to prevent stretching and tearing especially of the lower margin of the pocket opening.

In the drawings:

Figure 1 is a view of a portion of a garment exhibiting a pocket opening provided 20 with my invention.

Figure 2 is a similar view in detail with portions of the garment and pocket margin cut away to show a particular preferred installation of my reenforcing means.

Figure 3 is an alternative structure for use in certain types of garments.

Like parts are identified by the same reference characters throughout the various 30 views.

I have shown in the drawings only a portion of a fabric or leather garment 1 provided with a pocket 2 which may be formed as a concealed pocket or as a "patch" pocket, the opening being formed merely as a slot 3. It is at the top and bottom margins of the pocket opening 3 that my improved reenforcing means is installed as indicated generally at 5 and 6 in Figure 1.

40 The reenforcing strip 9 which I provide in my construction is of light, thin, flexible material preferably of thin steel, celluloid or so-called whale bone and is of substantial width. About this strip of reenforcing material I provide an encasing tube 8 of fabric, preferably some soft long wearing material in which the reenforcing strip is snugly secured and the entire assembled strip and tube are in turn held in place along the upper or 45 lower margins 5 and 6 of the pocket by a fold

of the material of which the garment is made, or if preferred, a fold or welt 7 of leather or other long wearing material may be sewed around the tube 8.

The strips of reenforcing material when in place along the margins of the pocket are so positioned that the edges of the strips register with each other to close the slotted opening 3 and therefore the width of the strip 9 is perpendicular to the strains placed upon the margins of the pocket by weights therein.

55 Preferably my reenforcing strip should be installed in both the upper and the lower margins of a pocket thereby insuring a straight even closure of the pocket opening 60 but mere reenforcement of the lower margin will tend to hold that margin closely against the body of the garment and in closed position as indicated in Figure 3.

65 As an additional reinforcement to assist 70 the preservation of the general form of a garment equipped with my form of pocket structure despite heavy pocket loads, I have provided at 11 for a reenforcing tape 12 which is secured in the aperture 11 and then sewed 75 into the body 1 of the garment at 13.

Even though the reenforcing strip is rounded at 10 and carefully protected at its end, the strip may cause friction destructive 80 of the body of the garment. The tape 12 materially lessens the possibility of such friction and also assists the strip in maintaining 85 the straight edge of the pocket.

As shown in Figure 2 in garments provided 85 with reenforcing strips in both margins of the pocket opening I leave a space at 14 to permit easy access to the pocket by providing room for the fingers of the user to be inserted.

90 A pocket equipped with my improved device will open easily under lateral pressure so as to admit objects into the pocket, for the extreme lateral flexibility of the reinforced edges will permit both the top and bottom edges of the pocket opening to flex to any reasonable extent. It will be obvious however, 95 that no matter how heavy the load in the pocket the downward pull cannot be sufficient to cause the lower margin of the pocket opening to sag. Under the securing influence of 100

the tape 12 and with the tensile strength provided by the whalebone, steel or any of the other materials used as stays, the pocket cannot be stretched so as to permit the margin to sag.

5 The application of my device for pockets is not, of course, limited to garment pockets. The reenforcement is also necessary in pockets in the doors of automobiles, in suitcases, in trunks and many other articles where bulging 10 and torn pocket openings become unsightly and inefficient.

I claim:

In a garment, the combination with a pocket having an opening, a tubular welt extending along each side of the pocket opening, a separate longitudinally flexible stiffening strip in each of said welts, the opposed edges of the strips being spaced from each other throughout their length, and flexible straps extending from the ends of the strips and connected to the garment, said welts being sustained from each other in the plane of the material of the garment and the pocket being openable only by the flexibility 25 of said strips in a plane normal to the strips.

SAMUEL DAVIDOFF.
